UNITED STATES PATENT OFFICE.

EUGENE E. PERRIER, OF MATTAWA, ONTARIO, CANADA.

CAN-OPENER.

1,305,929.

Specification of Letters Patent. Patented June 3, 1919.

Application filed December 18, 1918. Serial No. 267,270.

To all whom it may concern:

Be it known that I, EUGENE E. PERRIER, a subject of the King of Great Britain, residing at Mattawa, in the Province of Ontario and Dominion of Canada, have invented new and useful Improvements in Can-Openers, of which the following is a specification.

This invention relates to can openers, the object in view being to provide a simple and efficient can opener which is permanently attached to a can thereby particularly adapting the can opener for tourists, campers and others who are not obliged to carry 10 along a special or separate can opener which is liable to become lost or misplaced.

Another object of the invention is to provide a can opener which is folded in relation to the can when not in use and which 20 will not interfere with the compact shipping and storage of the cans nor the close arrangement of said cans upon the shelves in stores and storage depots.

With the above and other objects in view 25 the invention consists in the novel construction, combination and arrangement herein fully described, illustrated and claimed.

In the accompanying drawing:—

Figure 1 is a perspective view of the can 30 opener shown in its applied relation to a can and folded.

Fig. 2 is a fragmentary view of the can with the opener removed.

Fig. 3 is a fragmentary vertical section 35 showing the can opener folded in relation to the can.

Fig. 4 is a similar section showing the can in its operative or useful position.

Fig. 5 is a fragmentary section illustrating 40 the joint between the handle and the body of the can opener.

Fig. 6 is a bottom plan view of the device showing the guide groove.

The can opener contemplated in this invention comprises, in the preferred embodiment thereof, a radius bar 1 which constitutes the main body of the device, and an extension bar or piece 2 which is connected to the radius bar 1 by means of a hinge 3.

The hinge 3 occurs immediately adjacent 50 to the edge of the can as shown in Fig. 1 thus enabling the extension piece or bar 2 to lie snugly against the side of the can as shown in the same figure. The top of the can is formed with a depression or recess 55 4 to receive the radius bar 1 and permit

the same to lie flush with the top of the can. If desired the side of the can may be formed with a recess to receive and house the extension bar or piece 2. 60

Connected to the extension bar 2 and extending outwardly therefrom, in the use of the device, is a handle 6 having an enlarged end flange or head 7 to enable a firm grasp to be obtained thereon. The handle 6 is 65 connected to the extension piece or bar 2 by means of a hinge 8 of the knuckle joint type embodying stop shoulder 9 for sustaining the handle 6 at a right angle to the extension piece 2. 70

When not in use, the handle 6 lies close to the can as shown in Fig. 1.

11 designates a cutter or cutting blade which is connected to the radius bar 1 by means of a hinge 12 and is brought to its 75 operative position by means of a spring 13 arranged adjacent to the hinge joint as shown. When the device is folded the cutter 11 lies against the bottom of the radius bar 1 and upon the top of the can. As soon 80 however, as the device is slightly lifted, the spring 13 thrusts the cutter into operative position, the cutter being then forced downwardly through the top of the can. The device as a whole is connected to the top 85 of the can by means of a pivot 15 which is shown in the form of a rivet.

The manner of operating the can opener may be described as follows:—

The handle 6 is first grasped and moved 90 outwardly to a position at a right angle to the extension bar 2 and the handle is then pushed upwardly until said extension bar 2 lies in the same plane as the radius bar 1. The other end of the device as a whole is 95 then lifted sufficiently to enable the spring 13 to move the cutter 11 to a position at a right angle to the radius bar. This positions the point of the cutter directly against the top of the can about one-eighth of an 100 inch from the edge thereof. Downward pressure is then exerted upon the outer end of the radius bar until the cutter has penetrated and punctured the can. Then the handle 6 is moved in a circular path causing the cutter 11 to cut through the can in a circular path until the top of the can has either been entirely severed or partially severed sufficiently to enable the same to be bent upwardly and backwardly in order that the contents of the 110 can may be removed. If desired, the top

of the can may be provided with a circumferential depression or slit at a point to be engaged by the point of the cutting blade, so as to facilitate the operation of the cutter. 5 In instances where the top is slit, so as to divide the same, the meeting edges of the slitted portion and the top proper are connected by solder, which may be also true when the top is provided with a weakening 10 depression.

10 I claim:—

1. The combination with a can, of a can opener embodying a radius bar pivotally attached to the top of the can at a central 15 point, an extension bar hinged to the outer end of said radius bar and movable to an arc of substantially ninety degrees, an operating handle hinged to said extension bar and adapted to be swung to an arc of substantially 20 ninety degrees and a spring pressed cutter, having a hinged connection with said radius bar adjacent to the edge of the can.
2. In a can opener, the combination with 25 a can, of a can opener embodying a radius bar pivotally connected to the top of the can at the center thereof, an extension bar

hinged to the outer end of said radius bar and adapted to be swung to an arc of substantially ninety degrees, a handle hinged 30 to said extension bar and adapted to be swung to an arc of substantially ninety degrees, a cutter hinged to the underside of said radius bar and confined between said radius bar and the top of the can, and 35 yieldable means for throwing said cutter to a position substantially at a right angle to the radius bar when the latter is lifted.

3. In a can opener, the combination of a can having a depression in the top thereof, 40 and a can opener comprising a radius bar pivotally connected to the center of the top of the can and normally resting in the recess therein, an extension bar hinged to the outer end of the radius bar and normally 45 resting against the side of the can, a handle hinged to said extension bar and a cutter hinged to the underside of the radius bar and a spring for thrusting said cutter to its cutting position upon the lifting of said 50 radius bar at the outer end thereof.

In testimony whereof I affix my signature.

EUGENE E. PERRIER.
